DESK TRAY

Willie L. Rogers, Pennington Gap, Va.

Application February 5, 1954, Serial No. 28,874

Term of patent 14 years

(Cl. D74—1)

FIG. 1

FIG. 2

FIG. 3

FIG. 4

FIG. 5

To all whom it may concern:

Be it known that I, Willie L. Rogers, a citizen of the United States, residing at Pennington Gap, in the county of Lee and State of Virginia, have invented a new, original, and ornamental Design for a Desk Tray, of which the following is a specification, reference being had to the accompanying drawings, forming a part hereof.

Figure 1 is a top plan view of a desk tray, showing my new design;

Figure 2 is a front elevational view;

Figure 3 is a rear elevational view;

Figure 4 is a bottom plan view; and

Figure 5 is an end elevational view thereof.

The portions of the drawing shown in broken lines are for illustrative purposes only.

I claim:

The ornamental design for a desk tray, as shown and described.
